United States Patent Office.

F. B. MORSE, OF NEW HAVEN, CONNECTICUT.

Letters Patent No. 77,399, dated April 28, 1868.

IMPROVED PACKING FOR CARRIAGE-SHACKLES.

The Schedule referred to in these Letters Patent and making part of the same.

TO ALL WHOM IT MAY CONCERN:

Be it known that I, F. B. MORSE, of New Haven, in the county of New Haven, and State of Connecticut, have invented a new Improvement in Elastic Packing for Carriage-Shackles; and I do hereby declare the following, when taken in connection with the accompanying drawings, and the letters of reference marked thereon, to be a full, clear, and exact description of the same, and which said drawings constitute part of this specification, and represent, in—

- Figure 1, a side view,
- Figure 2 a top view,
- Figure 3 a central section, and in
- Figure 4 the packing detached.

This invention relates to an improvement in the construction of the elastic pad or packing which is inserted into the shackle behind the coupling, to prevent rattling, and is designed more particularly for the shaft-coupling patented to me, April 4, 1865; and to enable others to construct this improvement, I will proceed to describe the same as illustrated in the accompanying drawings.

A is the coupling, B the clip, upon which the ears C C are formed, through which, and the coupling, a bolt, D, passes to pivot the coupling between the ears. In the rear of the coupling a recess, a, is formed, as seen in fig. 3, and denoted in broken lines, fig. 2. E, the packing, is formed of India rubber, or other suitable material, with a projection, F, corresponding to the recess in the shackle, and a lip, f, upon its upper edge, so as to set over the top of the shackle, as seen in the drawings, the said lip covering the joint, and giving a finished appearance to the shackle, and also serves to aid the projection F in holding the packing in its place. The forward or front part of the packing is formed concave, to correspond to the surface of the coupling.

Owing to this construction, the projection F prevents the working of the packing, and the lip f covers the joint, so that the packing need be only sufficiently large to fill the space between the coupling and the clip, whereas, when put in in the plain block-form of the Chapman packing, it is necessary to compress the packing to a great degree in order to secure it in its position, consequently using from two to three times the quantity of rubber or material used in the formation of the packing.

Having thus fully described my invention, what I claim as new and useful, and desire to secure by Letters Patent, is—

The packing herein described as an article of manufacture, and consisting of block E, with the projections F and lip f, as set forth.

Witnesses.
